UNITED STATES PATENT OFFICE.

HUGH C. LORD, OF ERIE, PENNSYLVANIA.

TYPE BAR FOR TYPEWRITERS.

Application filed January 9, 1922. Serial No. 527,908.

To all whom it may concern:

Be it known that I, HUGH C. LORD, a citizen of the United States, residing at Erie, in the county of Erie and State of Pennsylvania, have invented new and useful Improvements in Type Bars for Typewriters, of which the following is a specification.

The invention is designed to improve the type-bar action. This is accomplished by 10 making the type-bar itself yielding intermediate its ends either by forming the type-bar of spring metal or by jointing the type-bar between its ends. Where this is done and the bar is sufficiently yielding to permit 15 the type end to lag with the initial impulse of the bar a very much higher velocity of the type end may be secured at the moment of impact with the platen. This is accomplished, because with the initial impulse of 20 the bar the type end lags between the general alinement of the bar for a part of the stroke and then as the type-bar end acquires motion centrifugal force begins to assert itself and as a result the type end is 25 accelerated so that at the moment of impact it has reached a position approximately in alinement with the shank of the type-bar and during what might be termed this catching up movement of the type end it has not 30 only the normal acceleration due to the swinging of the type-bar as a whole but also the acceleration incident to the swinging to alinement with a result that there is a very 35 much higher velocity at the moment of impact and a sharper and more pronounced impact. At the same time the initial movement of the bar is cushioned, thus relieving the operator of the dead shock of the unresilient bar.

40 The invention is illustrated in the accompanying drawings as follows:—

Fig. 1 shows a side elevation of a type-bar action.

45 Fig. 2 shows a similar view of a modification.

1 marks the platen, 2 the type, 3 the bar, 4 the bar shank, 5 a pivot for the shank, 6 the ordinary cam slot in the shank, 7 an arm of a bell crank lever having a pin 8 operating in the slot 6, 9 a pivotal mounting having a bell crank, 10 a slot in the opposite arm of the bell crank, 11 a pin operating in the slot and carried by the key lever

12, 13 a pivotal mounting for the key lever, and 14 the key. These parts are all of ordinary construction with the exception of the bar 3 which is formed of resilient spring metal preferably flat wire and is of sufficient resiliency with relation to the weight of the type end of the bar to have a pronounced lag as indicated in dash lines with the initial movement of the bar and swing into practical alinement with the shank at the moment of impact.

In Fig. 2 the structure is similar except 65 that the type bar is made of rigid material and of the parts 3^a, and 3^b and hinged at 3^c. A spring 3^d is secured to a projection 3^e on the end of the part 3^a and anchored through a perforation 3^f on the shank. With this 70 structure the end 3^a swings back on the hinge with the initial movement and as the bar proceeds swings to alinement through the influence of centrifugal force reaching this alinement at approximately the point 75 of impact.

What I claim as new is:—

1. A swinging type-bar for typewriters carrying a type at its end and yielding intermediate its end with an initial writing 80 impulse to permit a lagging of the type end with an added acceleration as the type end swings to alinement under the influence of centrifugal force.

2. A swinging type-bar for typewriters 85 carrying a type at its end and resiliently yielding intermediate its end with an initial writing impulse to permit a lagging of the type end with an added acceleration as the type end swings to alinement under the influence of centrifugal force.

3. A swinging type-bar for typewriters carrying a type at its end, said bar being formed of resilient material and yielding intermediate its end with an initial writing 95 impulse to permit a lagging of the type end with an added acceleration as the type end swings to alinement under the influence of centrifugal force.

4. In a typewriter, the combination of a 100 key lever; a platen; a type bar action; and a swinging type bar operated by the lever against the platen, said type bar yielding intermediate its end with an initial writing impulse to permit a lagging of the type end 105 with an added acceleration as the type end

swings to alignment under the influence of centrifugal force at approximately the moment of impact.

5. In a typewriter, the combination of a key lever; a platen; a type bar action; and a type bar formed of resilient material and yielding intermediate its ends with an initial writing impulse to permit a lagging

of the type end with an added acceleration as the type end swings to alignment under the influence of centrifugal force at approximately the moment of impact.

In testimony whereof I have hereunto set my hand.

HUGH LORD.
